UNITED STATES PATENT OFFICE.

RAMON FEBLES, OF HARRISBURG, PENNSYLVANIA.

TOOL.

No. 813,412.

Specification of Letters Patent.

Patented Feb. 27, 1906.

Application filed October 22, 1904. Serial No. 229,663.

To all whom it may concern:

Be it known that I, RAMON FEBLES, a citizen of the United States of America, and a resident of Harrisburg, in the county of Dauphin, State of Pennsylvania, have invented certain new and useful Improvements in Tools, of which the following is a specification.

This invention relates to a tool especially adapted for use in the packing of cigars in boxes or in the subsequent handling of the boxes.

The object of my invention is to provide a complete tool which will serve all the functions of the various tools now used by cigar-packers and furnish in one article an implement which will permit the packer to measure the depth and width of the box, to trim the cigars when necessary, and to serve as a hammer to close the box.

A further object of my invention is to provide a tool which when it is necessary to open the box will enable the user to easily sever the labels and revenue-stamp, to easily open the box, to remove the tack or brad therefrom, and to readily sever the ribbons with which the cigars are tied.

My invention therefore consists in the tool or implement as illustrated in the accompanying drawings and as will be hereinafter more particularly described and then definitely claimed at the end hereof.

In the drawings which accompany and form part of this application, Figure 1 is a side elevation of my tool with the blades partly opened and with parts broken away in order to show the locking device herein-after referred to. Fig. 2 is an edge view of the same.

Referring to the drawings, A and B represent the two blades, which may be pivoted together at C in the usual or ordinary manner. One of these blades is purposely made much longer than the other, as clearly shown in the drawings, and that part of the longer blade which projects beyond the shorter blade is formed especially for the purpose of opening cigar-boxes and also serving to prevent the cigars from being injured in the cutting of the ribbons, as will be hereinafter described.

This longer blade A is provided at one end with a tapering end a, which is of the shape shown in Fig. 2, so that it may be readily inserted between the lid and the box proper and the lid thereby opened. On one side of the longer blade A is a projection D, which

provides the double function of preventing the point a from entering too far into the box, and thus bruising the cigars, and also serving the purpose of a hammer when it is desired to again fasten the lid. The blade A is also provided with a notch E for the purpose of withdrawing the tack or nail after the lid is opened.

The blade B is provided at its point with a very sharp edge b, which is especially adapted to permit the user to run this edge through the labels and revenue-stamp immediately over the line of separation between the lid and the sides of the box. This part b is of necessity made very sharp, and in order to prevent it from injuring the user when the tool is used to pry open the lids of the boxes I employ a spring - actuated lock. (Shown in Fig. 1.) This lock comprises a bolt F, working in a slot in the handle G, the bolt being provided with a finger H, by which it may be operated. When it is desired that this bolt shall not be in operative position, the operator draws the finger H backward and into the right-angled slot I, (shown in Fig. 2,) and the bolt is withdrawn, as shown in Fig. 1. When it is desired to lock the two blades of the tool in their closed positions, all the operator has to do is to close the blades and then release the finger h, when the bolt will pass into the bolt-opening, (indicated at K in dotted lines in Fig. 1.)

I have mentioned that one blade is purposely made much longer than the other and that this is done for two purposes—the first to trim the tool to be used as a box-opener, and, second, for the purpose of resting the longer blade on one edge of the box while the operator inserts the shorter blades between the cigars, and thereby cuts the ribbons. By resting the longer blade on the opposite edge of the box the tool is steadied, so that there is no danger of cutting any of the cigars.

In packing cigars it is sometimes necessary to temporarily insert a tack in the bottom of the box, and this tack afterward has to be withdrawn. In order to permit this to be readily done, I form two slots L and M in the handles of the blades, so that either one of these handles may be inserted in the box and the tack easily withdrawn. This permits the operator to withdraw a tack from the bottom of the box even when the tack is in the corner of the box and in such a position as would prevent the user from withdrawing the tack by using the tack-puller E in the

blade A. It will also be observed that the slots E, L, and M are of different sizes in order that different-sized tacks may be pulled, two of these being for small-sized tacks and 5 the other for larger ones. It will also be observed that the point a is sufficiently broad to be used as a screw-driver when necessary, and owing to the fact that it is quite thin it can also be inserted in the box for the purpose of pressing the front side of the box outward, which is often necessary in packing cigars. When this blade is used to open the box, as before described, the projection D, which is so situated that it is between the fingers and the box, prevents the blade from entering so far as to allow the fingers on the hand from contacting with the front of the box. Thus the hand is not liable to receive splinters from a rough box or be torn by a 15 projecting tack. The edge b' of the other blade B is formed into a file, which is often found handy during the operation of packing cigars. The end b of this same blade will also be found very useful in scraping off the color- 20 marks from the box when it is necessary to change the marks during the operation of packing the cigars.

From the foregoing and the accompanying drawings it will be seen that I have produced a tool which in addition to forming an effective pair of scissors will also be found of great service to cigar-packers and also to those employed in cigar-stores, where it is necessary to constantly open cigar-boxes for the 35 sale of cigars.

What I claim as new is—

1. As a new article of manufacture, a tool or implement comprising a pair of scissors having blades of different length, the shorter 40 blade being provided with an acting end, the longer blade being tapered to act as a box-opener, and a stop on the longer blade whose stop-face is forward of the cutting-terminal of the shorter blade when closed, whereby 45 the same is protected, substantially as described.

2. As a new article of manufacture, a tool or implement comprising a pair of scissors having blades of different length, the shorter 50 blade being provided with an acting end, the longer blade being tapered to act as a box-opener, a stop on the longer blade whose stop-face is forward of the cutting-terminal of the shorter blade when closed, whereby the 55 same is protected, and releasable means for

locking the blades in closed position, substantially as described.

3. As a new article of manufacture, a tool or implement comprising a pair of scissors having blades of different length, the shorter 60 blade being provided with an acting end, the longer blade being tapered to act as a box-opener, and a stop on the longer blade having a flat face and whose stop-face is between the ends of the blades when closed, whereby 65 the shorter blade is protected, substantially as described.

4. As a new article of manufacture, a tool or implement comprising a pair of scissors having blades of different length, the shorter 70 blade being provided with an acting end, the longer blade being tapered to act as a box-opener, a stop on the longer blade having a flat face and whose stop-face is between the ends of the blades when closed, whereby the 75 shorter blade is protected, and releasable means for locking the blades in closed position, substantially as described.

5. As a new article of manufacture, a tool or implement comprising a pair of scissors 80 having one of its blades longer than the other, the shorter blade having at its outer end a cutting edge, and means for locking the blades closed, substantially as described.

6. As a new article of manufacture, a tool 85 or implement comprising a pair of scissors having one of its blades longer than the other, the shorter blade being sharpened, and a spring-actuated bolt arranged to lock the blades closed, substantially as described. 90

7. As a new article of manufacture, a tool or implement comprising a pair of scissors having one of its blades longer than the other, the shorter blade having its end sharpened, and a spring-actuated bolt for locking said 95 blades closed, substantially as described.

8. As a new article of manufacture, a tool or implement comprising a pair of scissors with one blade longer than the other, said longer blade having a tapering end adapted 100 to opening boxes, and the other a sharpened end adapting it to cut the labels, and means for locking the two blades closed, substantially as described.

Signed by me at Harrisburg, Pennsylvania, this 20th day of October, 1904. 105

RAMON FEBLES.
